UNITED STATES PATENT OFFICE.

JONAS NORTHROP, OF HOPEDALE, MASSACHUSETTS, ASSIGNOR TO HOPEDALE MANUFACTURING COMPANY, OF HOPEDALE, MASSACHUSETTS, A CORPORATION OF MASSACHUSETTS.

AUTOMATIC WEFT-REPLENISHING LOOM.

1,142,725.

Specification of Letters Patent.

Patented June 8, 1915.

Application filed October 9, 1914. Serial No. 865,850.

To all whom it may concern:

Be it known that I, JONAS NORTHROP, a citizen of the United States, residing at Hopedale, in the county of Worcester and State of Massachusetts, have invented certain new and useful Improvements in Automatic Weft-Replenishing Looms; and I do hereby declare the following to be a full, clear, and exact description of the invention, such as will enable others skilled in the art to which it appertains to make and use the same.

The present invention relates to an improvement in automatic weft replenishing looms.

When the Northrop loom was first invented, it was proposed to apply the weft replenishing mechanism to old looms, but without success, as it was found that the condition of old looms varied so widely as to prejudice the successful application of the replenishing mechanism to the loom in the correct position with relation to the lay. An attachment for a loom which had been under operation for ten years would require considerable alteration in order to adapt it to a loom which had been in operation for thirty years, and the manufacturer achieved no success in introducing the loom into commercial use until a complete loom was built having embodied in it the weft replenishing mechanism. Since that time other manufacturers have made similar endeavor to apply weft replenishing mechanism to old looms, but heretofore without success. It will be observed that the condition of wear of the rocker shaft would vary the position of the lay beam as much sometimes as $\frac{1}{8}$ of an inch, and in order correctly to position the weft replenishing mechanism with relation to the lay this had to be taken into consideration. Again, in applying the attachment to different kinds of old looms, a great number of patterns for the hopper plate were required, each having a foot of different form to adapt it to the particular loom to which it was to be attached. This would have required a large number of expensive patterns, thereby increasing the manufacturing cost to a very considerable degree, as the greater part of each pattern, and the most expensive part, would be identical with the greater part of all the other pat-

terns, and only a comparatively inexpensive portion would be different.

One of the objects of this invention is to produce a weft replenishing mechanism attachment adapted for application to old looms, having the capacity of correct adjustment of the position of the mechanism to the lay irrespective of the condition of wear of the rocker shaft, and another object of the invention is to produce a construction by virtue of which the cost of the attachment can be reduced.

To these ends the invention consists in the attachment hereinafter described and particularly defined in the claims, in which provision is made for relative adjustment of the attachment to the lay beam and in which the hopper plate is made of two or more parts so that the more complicated and expensive parts of the hopper plate may be the same for all attachments, and the foot or bracket by which it is attached to the loom may be a separate casting, comparatively inexpensive, and adapted in each case for the particular loom to which the attachment is to be applied.

In the accompanying drawings illustrating the preferred form of the invention, Figure 1 is an elevation of a portion of a loom with the weft replenishing mechanism attached thereto; Fig. 2 is a left-hand end elevation of the hopper plate and hopper plate foot or bracket illustrating the mode of attachment of the lay to the breast beam and showing the position of the lay with relation thereto; Fig. 3 is a perspective view of a hopper plate embodying the present invention adapted for use with all types of looms to which the attachment may be applied; and Figs. 4, 5 and 6 illustrate different feet or brackets by which the hopper plate is attached to different forms of looms.

The illustrated embodiment of the invention is described as follows:—The weft replenishing mechanism is shown as mounted on the right-hand end of the breast beam B of the loom, and the upper portion of the end frames F are shown. The hopper plate 1 which is the frame of the weft replenishing mechanism is provided with a vertical slot or guideway 2 which receives the plate or upright 3 of the hopper plate bracket or foot indicated in a general way by the refer-

ence character 4. The hopper plate carries the transfer, transfer latch, shuttle feeler and associated parts. The hopper plate bracket or foot 4 has the base 5 which 5 is provided with longitudinal slots 6 which receive bolts by which the base is attached to the breast beam B. The breast beam is slotted transversely at 7 so as to permit lateral adjustment of the base on the breast 10 beam. By means of these two slots the hopper plate bracket or foot may be secured in correct position on the breast beam, the slots being provided for longitudinal and transverse adjustment. The hopper plate upright 15 3 fits the guideway or slot 2 and it is provided with vertical slots 11 which receive the bolts 12 by which the hopper plate is secured to the hopper plate bracket or foot. The hopper plate is provided with a boss 13 20 which receives an adjusting screw 14, having a set nut 15, the lower end of which set screw takes into a recess 16 in the upper end of the upright 3 of the hopper plate bracket or foot.

25 In applying the weft replenishing attachment to the loom, proper slots are first cut in the breast beam. Then the hopper plate bracket or foot is secured to it in approximate position. Thereafter the hopper plate 30 is mounted on the upright of the bracket or foot and tentatively secured in place by the bolts 12. Then when the various parts of the weft replenishing mechanism are mounted on the hopper plate, the device as a whole 35 is adjusted to the proper position to bring its parts into correct vertical, lateral and longitudinal position with relation to the lay. With different looms the different feet 17, 18 and 19, or others, as the case may 40 be, are employed and with all of the attachments a common hopper plate is employed.

It will be observed that by making the hopper plate in two or more parts, an important manufacturing economy is secured, 45 as the number of patterns required for the hopper plate is reduced to one, irrespective of the form of the loom to which the attachment is to be applied and that the comparatively inexpensive hopper plate bracket or 50 foot is the only piece of the mechanism which is required to be particularly adapted to the loom to which the attachment is to be applied. It is also to be observed that the provision for vertical adjustment between 55 the hopper plate and the hopper plate bracket or foot, which insures a correct vertical position of the weft replenishing mechanism with respect to the lay, is of great importance in maintaining the looms in operative 60 condition. It has been observed that in weft replenishing looms after a comparatively few years of life the wear of the loom is such as to require the replacement of the entire loom, involving the user of the looms 65 in a large expense, whereas in looms pro-

vided with the weft replenishing attachment of the present invention, such replacement of entire looms is unnecessary. For example, if the condition of the old loom to which the present weft replenishing attachment is applied were such when the attachment was put on that the lay should be considerably below its normal operative position, due to wear of the rocker shaft bearing, the hopper would have a certain position with relation to the lay in such worn condition. If now the lay rocker shaft bearing should be renewed, such renewal would involve raising the lay beam, it might be to such a substantial extent as to throw 70 the weft replenishing mechanism out of operative relation thereto, and in the present construction it will only be necessary to loosen the bolts by which the hopper plate is secured to the hopper plate bracket or 75 foot and to screw down the adjusting screw 14 so as to lift the hopper plate up a distance sufficient to bring the weft replenishing mechanism again into proper operative relation to the lay, whereupon the bolts securing the hopper plate to the hopper plate bracket or foot will again be tightened and the adjustment thereby completed.

It is of the utmost importance, in order to 80 secure the efficient operation of the loom, 95 that the weft replenishing mechanism should be susceptible of being adjusted to the correct position with relation to the lay irrespective of the condition of wear of the loom at any given time. This attachment 100 has been successfully applied to old looms in large numbers, and in widely varying conditions of wear, and with a great economy to the mill by reason of the saving secured to it in being enabled to apply a small attachment to the looms which may be long retained in operation, instead of being junked after a comparatively few years of 105 operation. The construction is not only of the utmost importance in connection with 110 the application of weft replenishing attachments to old looms, but it is of great importance in connection with new looms, for it will greatly prolong the usual life of a loom especially constructed as a weft replenishing loom, continuing it in operation 115 long beyond the period at which such loom otherwise would be required to be replaced by a new loom. Especially constructed weft 120 replenishing looms have required replacement after no longer period of use than fifteen or twenty years. This attachment 125 has been applied to plain looms forty years old, in large numbers and with great success.

So far as I am aware I am the first to make a hopper plate for weft replenishing mechanism in two parts, and I desire to claim this invention broadly as it contributes to two important results above point. 130

ed out, to wit, economy of manufacture and durability of the loom.

Having thus described the invention what is claimed is:—

5. 1. A weft replenishing attachment for looms having, in combination, a frame for the attachment having provision for supporting the operative parts of the mechanism and a bracket or foot separate from the attachment frame constructed and arranged for attachment to the frame of a loom said attachment frame and foot having coöperating portions fitting each other and contributing to correct positioning of 10 the parts to each other.

15. 2. A weft replenishing attachment for looms having, in combination, a frame for the attachment having provision for supporting the operative parts of the mechanism, and a bracket or foot separate from the attachment frame constructed and ar- 20

ranged for attachment to the frame of a loom, said attachment frame and bracket having provision by virtue of which the weft replenishing mechanism may be ad- 25 justed in position with relation to the operative parts of the loom.

3. A weft replenishing attachment for looms having, in combination, a frame for the attachment having provision for supporting the operative parts of the mechanism, and a bracket or foot constructed and arranged for attachment to the frame of a loom, having provision for vertical adjustment of the weft replenishing mechanism 30 on the bracket or foot by which the attachment is supported on the loom. 35
